UNITED STATES PATENT OFFICE.

RAY P. JACKSON, OF WILKINSBURG, PENNSYLVANIA, ASSIGNOR TO
WESTINGHOUSE ELECTRIC & MANUFACTURING COMPANY, A COR-
PORATION OF PENNSYLVANIA.

HAND-OPERATED ELECTRIC-CIRCUIT CONTROLLER.

No. 852,380.

Specification of Letters Patent.

Patented April 30, 1907.

Application filed December 18, 1905. Serial No. 292,237.

To all whom it may concern:

Be it known that I, RAY P. JACKSON, a citizen of the United States, and a resident of Wilkinsburg, in the county of Allegheny and State of Pennsylvania, have invented a new and useful Improvement in Hand-Operated Electric-Circuit Controllers, of which the following is a specification.

My invention relates to hand-operated electric circuit controllers and particularly to such controllers as are adapted for use with electric railway vehicles.

The object of my invention is to provide means for automatically returning a controller drum to a predetermined position, that shall be simple and durable in construction and that shall exert a substantially constant returning force whatever may be the angle through or the direction in which the drum has been moved.

It is generally desirable, particularly in railway vehicle service, to provide means for automatically returning the movable contact-bearing member of the controller or master switch to a predetermined "off" position so that the motors governed thereby may be brought to rest in case the operator becomes incapacitated. The desired result has usually been accomplished by means of two springs which operate independently and oppositely to move the controller drum to the "off" position. The means just mentioned is open to objection because the space occupied by the springs is large and also because the returning force varies materially as the drum rotates through different angles.

The mechanism of my invention comprises, in general, a single helical spring the axis of which is substantially perpendicular to that of the shaft of the controller and in a different plane, and which is so mechanically connected to the shaft by a pair of links that the spring is compressed from one end when the handle is rotated in one direction and from the other end when the handle is rotated in the opposite direction. In this way the total length of the spring is utilized in both directions and a substantially uniform pressure is exerted throughout the entire range of drum rotation.

My invention is illustrated in the accompanying drawings, in which

Figure 1 is a front elevation of a master controller constructed in accordance therewith, the cover being removed to show the

spring mechanism, which is further illustrated in detail in Figs. 2, 3, 4 and 5.

Referring to the drawings, the master controller 1 comprises a substantially cylindrical contact-carrying member 2 having a shaft 3 one end of which may be journaled in a boss on the rear plate 4 on the controller casing and the other end of which is provided with a bearing 5 that is supported by a U-shaped bracket 6 which is rigidly attached to the base of the controller casing.

The rotatable, contact-carrying member 2 may be rotated from its "off" position in either direction by any convenient means, and, in order to bring it back to a predetermined "off" position, when it is released, I provide a returning mechanism, the main member of which is a spring 9 that is mounted upon a stationary rod 10. The ends of the spring 9 are engaged by a pair of members 11 and 12, which are loosely mounted upon the rod 10 and are respectively provided with ears or lugs 13 and 14 to which the outer ends of connecting links 15 and 16 are loosely attached.

A bushing 7 is rigidly keyed to the shaft 3 and is provided with ears or lugs 18 between which the inner ends of the connecting links 15 and 16 are pivoted. The links 15 and 16 are provided with longitudinal slots near their outer ends to receive connecting pins by which they are fastened to the members 11 and 12, so that, as the shaft 3 is rotated in one direction, the spring 9 is compressed from one end by the action of the member 12, which is forced along the rod 10 by the link 16, while the slot and pin connection between the link 15 and the member 11 permits said member to act as a stationary abutment for the corresponding end of the spring. When the shaft is rotated in the opposite direction, the spring is compressed from the opposite end by the member 11 and the link 15, while the member 12 serves as a stationary abutment for the corresponding end of the spring. In this way, a single spring is utilized, regardless of the direction of rotation of the contact-carrying member and it may consequently be made more flexible for a given space.

Although I have shown and described a specific detailed construction in connection with a master controller which is adapted to govern the control circuits of a railway vehicle equipment, my invention may obvi-

ously be applied to any convenient form of controller and I desire that variations in size, form and arrangement of details, however applied, which do not depart from the spirit of my invention shall be included within its scope.

I claim as my invention:

1. The combination with a rotatable shaft or rod, of means for automatically returning the shaft or rod to a predetermined position after it is rotated therefrom in either direction comprising a spring disposed in a plane perpendicular to the shaft, and lost motion connections between the ends of the spring and the shaft.

2. In a controller, the combination with a contact-carrying drum, of means for automatically returning the said drum to a predetermined "off" position, after it has been rotated in either direction, that comprises a compression spring and links that severally make operative connection between the drum and the ends of the spring for either direction of rotation.

3. In a controller, the combination with a rotatable, contact-carrying member, of means for automatically returning said member to a predetermined "off" position, when it is moved therefrom in either direction, that comprises a compression spring, a pair of longitudinally movable members which engage the ends of the spring and a pair of links that connect said longitudinally movable members to the contact-carrying member.

4. The combination with a rotatable shaft or rod, of means for automatically returning the shaft or rod to a predetermined position after it is rotated therefrom in either direction comprising a spring, and lost motion connections between the ends of the spring and the shaft.

5. In a controller, the combination with a contact-carrying drum, of means for exerting a substantially constant returning force upon said drum, when it is moved in either direction from a predetermined position, that comprises a single spring located in a plane substantially perpendicular to the axis of the drum and a pair of links having lost motion connections with the ends of the spring and interposed between the spring and the drum.

6. In a controller, the combination with a rotatable member and a shaft therefor having a bushing provided with laterally projecting ears, of means for exerting a returning force upon said rotatable member and its

shaft, when moved in either direction from a predetermined position, that comprises a spring, two engaging members and a pair of links interposed between said members and the bushing ears and attached to the spring engaging members by lost motion connections.

7. In a controller, the combination with a rotatable member and a shaft therefor having a bushing provided with laterally projecting ears, of means for exerting a returning force upon said rotatable member and its shaft, when moved in either direction from a predetermined position, that comprises a spring, two engaging members and a plurality of links that are pivotally attached to said projecting ears and have slot and pin connections with the spring-engaging members.

8. In a controller, the combination with a drum that is rotatable in either direction from its "off" position and a shaft therefor having a bushing at one end, of a helical spring the axis of which is substantially at right-angles to that of the drum shaft, a rod extending through the spring, compressing members loosely mounted upon the ends of the rod and engaging the ends of the spring, and links pivoted at their inner ends to the shaft bushing and having slot and pin connection at their outer ends with the spring-compressing members.

9. In a controller, the combination with a contact-carrying drum, of means for automatically returning the said drum to a predetermined "off" position, after it has been rotated in either direction, that comprises a spring and links that severally make operative connection between the drum and the ends of the spring for either direction of rotation.

10. In a controller, the combination with a contact-carrying drum, of means for automatically returning the said drum to a predetermined "off" position, after it has been rotated in either direction, that comprises a spring, and slotted links that make operative lost motion connection between the drum and the ends of the spring.

In testimony whereof, I have hereunto subscribed my name this 15th day of December 1905.

RAY P. JACKSON
